US00D775608S

(12) **United States Design Patent** (10) **Patent No.:** **US D775,608 S**
(45) **Date of Patent:** **** Jan. 3, 2017**

(54) **SPEAKER DIAPHRAGM**

(71) Applicant: **Yamaha Corporation**, Shizuoka (JP)

(72) Inventors: **Masao Noro**, Shizuoka (JP); **Soichi Takigawa**, Shizuoka (JP); **Kenichi Yoshinaga**, Shizuoka (JP); **Akihiko Nozaki**, Shizuoka (JP)

(73) Assignee: **Yamaha Corporation** (JP)

(**) Term: **14 Years**

(21) Appl. No.: **29/524,180**

(22) Filed: **Apr. 17, 2015**

(30) **Foreign Application Priority Data**

(57) **CLAIM**

A speaker diaphragm, as shown and described.

DESCRIPTION

FIG. 1 is a perspective view of a speaker diaphragm showing embodiments of our new design;

FIG. 2 is a side view of FIG. 1;

FIG. 3 is a front view of FIG. 1;

FIG. 4 is a top view of FIG. 1;

FIG. 5 is a bottom view of FIG. 1; and,

FIG. 6 is a cross-sectional view taken in the direction of line 6-6 as seen in FIG. 4.

The broken lines shown are included for the purpose of illustrating portions of the speaker diaphragm that form no part of the claim.
